UNITED STATES PATENT OFFICE.

ANTHONY NAINKA, OF LA CROSSE, WISCONSIN.

DESIGN FOR A SNAP-HOOK FRAME.

SPECIFICATION forming part of Design No. 34,247, dated March 19, 1901.

Application filed February 19, 1901. Serial No. 48,009. Term of patent 3½ years.

To all whom it may concern:

Be it known that I, ANTHONY NAINKA, a subject of the Emperor of Austria-Hungary, residing at La Crosse, in the county of La Crosse 5 and State of Wisconsin, have invented and produced a new and useful Design for Snap-Hook Frames, of which the following is a specification.

My invention is a design for the frame of a 10 snap-hook; and it consists in the shape and construction illustrated in the accompanying drawing.

The drawing is a plan view of a snap-hook frame embodying the design.

15 The reference-numeral 1 designates a metallic plate formed at one end with a rectangular opening 2 and recessed to form a longitudinal slot 3 of the irregular shape shown in the drawing, the wall 4 of the slot being 20 downwardly curved. The front end 5 of the slot is of rectangular form, forming an arm 6, the rear end 7 of which is curved and bev-

eled on its inner side. The front end 8 of the plate is rounded to semicircular form, and from the inner side of the rear end 9 of said 25 plate projects a perforated ear 10. The plate is formed adjacent to the slot 2 with a slot 11, extending longitudinally of the plate and of approximately triangular shape, the wall 12 of the said slot being curved, as shown. 30

The leading features of the design are the peculiar-shaped slot 3 and the transverse rectangular slot 2, and the minor feature of the design is the arm 6, with its beveled end 7, and the projecting perforated ear 10. 35

I claim—

The design for a snap-hook frame herein shown and described.

In testimony whereof I affix my signature in presence of two witnesses.

ANTHONY NAINKA.
